UNITED STATES PATENT OFFICE.

FRANK F. LANDIS, OF WAYNESBOROUGH, PENNSYLVANIA.

TRACTION-ENGINE.

SPECIFICATION forming part of Letters Patent No. 337,841, dated March 16, 1886.

Application filed January 18, 1886. Serial No. 188,894. (No model.)

To all whom it may concern:

Be it known that I, FRANK F. LANDIS, a citizen of the United States, residing at Waynesborough, in the county of Franklin 5 and State of Pennsylvania, have invented certain new and useful Improvements in Traction-Engines, of which the following is a specification, reference being had therein to the accompanying drawings.

10 My invention relates to the frame of the engine and the connections or fastenings uniting it to the boiler; and the objects of my invention are to combine and arrange the parts so as to retain them in their proper relative position without strains caused by unequal expansion and contraction, or by the jars and concussion to which traction-engines are subjected while upon rough roads.

In the accompanying drawings, Figure 1 is 20 a side view of a portion of the traction-engine frame adjacent to the traction-wheels, showing the rear portion of the boiler in dotted lines, and also the frame of the engine proper. Fig. 2 is a rear view of the traction-engine. Fig. 3 is a top view of the same, 25 showing the connections of the boiler with a transverse connecting-rod of the frame in the rear thereof. Fig. 4 is a top view showing the connections of the boiler with the lower connecting-rod of the frame. Fig. 5 represents, partly in elevation and partly in section, a sleeve-inclosed bolt used to connect 30 the housing of the frame to the boiler. Fig. 6 is a transverse vertical section, on a large scale, of one of the boiler-suspension bolts and its connections to the boiler and supporting-frame. Fig. 7 is a side view of a modified portion of the housing carrying the boiler-suspension bolts. Fig. 8 is a transverse vertical section through one of the brackets, connecting the forward end of the traction-engine frame to the boiler.

I have shown the invention as applied to one class of traction-engines, often called 45 "road-locomotives," and mounted upon springs; but I do not wish to be restricted to them, as it is also applicable to simpler machines used for farm-work.

In the drawings, A represents the rear part 50 of a boiler of the form commonly used in locomotives; and B in Figs. 1 and 2 represents in dotted outline a double engine, fully shown

and described in a companion application. Portions of the traction-engine sills are shown at D, on each side of the fire-box. Each sill 55 is formed of two flat bars or rails retained at a short distance apart by parting-blocks and bolted or riveted together. The forward end of the sills is usually fastened to the front corners of the fire-box by a suitable bracket, D', 60 the middle portion of which forms the separating-block between the rails of the sill. The rear side of each bracket is recessed to receive the heads of the connecting-bolts d', and its top and bottom are perforated to receive 65 the bolts or rivets d'', by which it is rigidly attached to the boiler. Near the middle of the length of the sills D, and between them, are bolted the housings C. They form in Fig. 1 the guides for the bearings C', from which are 70 suspended the spring-stirrups C'.

In Fig. 7 the springs are dispensed with, and an ordinary clamp-bearing is shown to receive the axle. The housings C form the connections between the sills D and the rear 75 end of the engine-frame B. Near the upper end of each housing, and at the rear thereof, it is surfaced and grooved to receive the bearings E' for the counter-shaft of the engine, and integral with said bearings is a cast bar, 80 E', that forms a rigid connection between them and between the upper ends of the housings independently of the engine-frame or the boiler.

Under the axle A', and between the sills D, 85 there is a flat bar, D', having its ends fastened to said sills, as shown in top view in Fig. 4; but in some class of engines I connect the sills by means of a bolt passing through a sleeve corresponding in length with the distance between said sills. To the front of the connecting-bar D' is centrally secured a casting, e, 90 vertically grooved at e', and to the rear face of the boiler there is attached a casting, e'', having a corresponding tongue, e'', which fits against 95 the sides of the groove e', but does not extend quite to the bottom of said groove, to allow space for the expansion of the boiler. A similarly vertically-grooved plate, e, is attached to the rear of the boiler opposite the horizontal bar E', that unites shaft-bearings 100 E, and said bar has a tongue, e'', to similarly enter the vertical groove in said upper plate, e.

To connect the upper end of the housings

C to the boiler, a bolt, E, is used on each side of the boiler. The rear end of said bolt E passes through the housing and preferably also through the shaft-bearings E' and its cap-plate, and carries a nut and jam-nut at its extreme end. The front end of each bolt E passes through brackets F, secured to the sides of the boiler, preferably in the same vertical plane that passes through the middle of the length of the cylinders B² of the engine, so that the ball-joint of the cylinder-carrying steam-dome (described in a companion application) being in the same transverse vertical plane there will be a corresponding expansion 15 of the connecting-bolt E and of the engine-frame, and consequently no strain upon these parts, and as the engine-frame is connected to the boiler at the front end only there will be no change in the relative position of the gearing shown in dotted lines at B'.

The back end of the boiler is carried by strong links H—one on each side—which are connected to the side of the boiler at or near the lower edge of the fire-box by means of 25 brackets G. In order to obviate the little side-draft caused by the links being an inch or two from the sides of the boiler, the brackets G are united by means of a link or brace, g, passing under the fire-box. The lower end 30 of each link H receives a bolt, d, that passes through the bracket G, while the upper end receives a bolt, c, that also passes through the lower end of the housings, but may pass direct through the sills.

35 The bottom of the engine-frame B is not rigidly bolted to the top of the housings, but the parts are held together at the joints D² by clamping-strips d². The feet of the engine-frame have flanges d³ on two sides, between 40 which the top of the housings and the strips d² fit loosely enough to allow said feet to slide thereon in the direction of the axis of the bolts E, and therefore all the pulling strains (produced by the gearing when in motion) 45 are taken by the bolts E, and as the latter are secured to the sides of the boiler by the brackets F and nuts upon the bolts the engine-bed B is not in any way strained by the expansion of the boiler. Therefore, the engine-bed has only to resist the shocks between 50 the crank-shaft bearings and the heads of the cylinder, as in all other engines.

Although the bolts E are important, they 55 may be dispensed with by making the engine-bed much heavier and stronger than with the above-described construction, and with said heavy bed all the strain on the top of the machine would have to be resisted by the steam-joint under the steam-dome.

60 The engine-frame has one bearing at the cylinder's end, while at the rear end it has two bearings—one upon each of the housings—and thus it has a three-footed base, and consequently a solid and easily-fitted bearing.

Having now fully described my invention, 65 I claim—

1. In combination with a boiler, the engine-frame rigidly secured to said boiler at its front end and movably secured to the housings or supporting-frame, substantially as and for the 70 purpose described.

2. The combination of a traction-engine boiler, the engine-frame rigidly secured to said boiler at its front end and movably secured to the housings or supporting-frame at 75 its rear end, with bolts or rods secured at their front end to the boiler in a plane passing transversely across the boiler and at their rear end to the housings or supporting-frame of the traction-engine, substantially as and for the 80 purpose described.

3. The combination of a traction-engine boiler, its housings, and sills D with brackets D', secured to the front end of the fire-box, and links H, having their lower end secured 85 to the rear end of the fire-box and their upper end to the frame-work, substantially as described.

4. The combination of a traction-engine boiler, its supporting-frame, housings, and 90 horizontal bar E², connecting said housings with the interlocking plates e and e², secured to the rear end of the boiler and to said horizontal bar, substantially as and for the purpose described.

5. An engine-frame rigidly secured at its cylinder's end to the top of a boiler, with its opposite or crank-shaft end movably secured to the housings or supporting-frame of the boiler and machinery of a traction-engine, 95 substantially as and for the purpose set forth.

6. In a traction-engine, the rear end of boiler supported by links H, pivotally attached at their upper ends to the supporting-frame, substantially as and for the purpose set forth. 105

7. The combination of a traction-engine boiler, the supporting-links H, and brackets G G, with a connecting or distance bar, g, substantially as and for the purpose set forth.

8. The combination of a traction-engine 110 boiler, the transverse braces D² E², and the interlocked, tongued, or grooved plates, as e e², substantially as and for the purpose set forth.

9. The combination of a traction or portable engine-boiler, its engine-bed having three bearing-points, a single rigid bearing to the boiler at the cylinder's end, and two sliding bearings at the opposite end, and connected to the supporting-frame or housings, substantially as set forth. 115

In testimony whereof I affix my signature in presence of two witnesses.

FRANK F. LANDIS.
